UNITED STATES PATENT OFFICE.

STEPHEN T. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,159,541.

Specification of Letters Patent.

Patented Nov. 9, 1915.

Application filed June 5, 1914. Serial No. 843,117.

To all whom it may concern:

Be it known that I, STEPHEN T. SMITH, a citizen of the United States, residing in Stamford, in the county of Fairfield and State of Connecticut, have invented certain new and useful Improvements in Type-Writing Machines, of which the following is a specification.

This invention relates to twin typewriting machines, in which two frames are mounted side by side, each frame carrying a set of type-bars and keys, each type set having a separate printing point, and a paper carriage mounted to travel in each printing zone and to cross over from one zone to the other; and one of the objects of the invention is to produce a compact, strong and durable device of this character.

One feature of the invention relates to the letter-feeding mechanism. Each set of type keys operates a separate escapement mechanism, usually comprising an escapement wheel and pinion, the latter running in mesh with a rack on the carriage to control the letter-feed movement of the carriage. The rack is of a length substantially equal to the distance between the pivots of the two escapement pinions, whereby upon the conclusion of the operation of one escapement train the operation of the other escapement train begins. The length of the rack may therefore be about equal to the length of the line written on either typewriter; in other words, the length of the line of writing may be equal to the distance between the pivots of the escapement wheels.

A front scale bar may be provided with scales to indicate the position of the carriage in each printing zone, each scale comprising a series of numbered graduations, and as the line of writing for one zone commences where the line of writing in the other zone is completed, the numbering of one scale commences where the other is concluded, so that there is no gap between the scales.

When the carriage is in the right-hand side of the machine, it may be fed along by operating the type keys or space key until the limit of the line of writing is reached, whereupon a further operation of said keys will not affect the carriage; but the letter-feed movement of the carriage which has thus been brought to the left-hand printing

zone, may be continued by operating the keys of the left-hand keyboard. Thus there is no point on the carriage that is not in the control of either one letter-feeding mechanism or the other.

The carriage may be mounted to travel on front and rear tracks, each of which may consist of a rail extending unbroken across both the machine frames, and said rails may be supported in the middle by brackets, which also serve to connect the machine frames. The front rail may be grooved to form a guideway or track in which run rollers on the carriage. One of the advantages of this arrangement in which the carriage runs across both machine frames on the same guide rails is compactness. In an ordinary single machine, the guide rails project a considerable distance at each side of the machine, this being necessary in order to give the carriage wide bearing on the rails and to permit the carriage to have a long travel. If two such machines were placed side by side with their rails abutting end to end, there would be considerable space between the machine frames, which in the present invention is not demanded, because the rails for the two machine frames are in a sense overlapped or merged into a single cross-rail permitting the frames to be placed together. The carriage while in the right-hand printing zone, rides onto a portion of the rail which belongs to the left-hand machine, and likewise while in the left-hand zone the carriage rides over from the left-hand portion of the rails to portions which belong to the right-hand machine. The front rail, extending across both machine frames, permits the rolls on the carriage to be widely separated, thus giving great stability to the carriage, the left-hand roll running over on the left-hand portion of the front rail while the writing of a line is being completed on the right-hand machine, and the right-hand roll running on the right-hand portion of the rail during the commencement of a line of writing on the left-hand machine. The room occupied by the twin machine is also much less than that which would be required by two machines set closely side by side with their carriages having stability equal to that of the twin machine.

The entire machine comprises a base, to

which the two main typewriter frames are secured by means of screws passing up into the usual threaded feet of said frames. At their upper portions the frames are also 5 rigidly joined by means of the brackets which support the carriage rails. This makes a very compact and rigid structure, produced with but little alteration in the component typewriting machines, and hence 10 readily manufactured.

Other features and advantages will hereinafter appear.

In the accompanying drawings, Figure 1 is a partly diagrammatic front elevation 15 view of the machine, the carriage being shown at the intermediate position where it passes from one printing zone into the other. Fig. 2 is a rear elevation view showing the carriage in full lines at the limit of its 20 travel in one direction and in broken lines at or near the opposite limit of travel. Fig. 3 is a view of the scale. Fig. 4 is a perspective view showing the letter-feed mechanisms and the type actions, the carriage rack being shown at the point of transfer from 25 the control of one escapement mechanism to that of the other. Fig. 5 is a sectional side elevation view of the machine, and Fig. 6 is a detail perspective view showing the arrangement of the front rollers on the 30 carriage.

Two machine frames A and B which may be substantially the same as that of the commercial Underwood typewriting machine, are mounted side by side on a base 1, being secured to the base by means of screw bolts 2, which extend upwardly through a flange *a* of the base 1, and are threaded into the machine frames, the bolts preferably extending into or through feet *b* on the frames. 35 The frames are also secured together by front and rear brackets 3 and 4 connected by screws 3^a and 4^a or otherwise to the tops of the machine frames. Each frame is provided with a separate keyboard comprising 40 a set of keys 5, mounted on key levers 6, fulcrumed on a rod 7, said levers connected through bell-cranks 8 to type bars 9, for swinging the latter upwardly and rearwardly about their fulcrum 10 to cause the 45 types 11 to strike against the front face of the platen 12. The platen is mounted on a carriage 13, which travels on front and rear guide rails 14 and 15 respectively. The carriage 50 may have a sliding connection with the rail 15 by means of lugs 16 on the carriage. The rail 15 may extend across both machine frames as shown in Fig. 2, being connected adjacent its ends to the outer ends 55 of the machine frames and also supported at the middle by the bracket 4. The front guide rail 14 also extends across both machine frames, being supported at its ends on the machine frames and may be supported 60 at the middle by the bracket 3.

The rail 14 may be formed in its inner face with a groove or channel forming a track for the rollers 17 on the carriage. A number of these rollers may be provided in order to give stability to the carriage 70 throughout its entire range of travel. As shown in Figs. 1 and 6, three rollers are provided, one at each end of the carriage and one at the middle. In this arrangement at least two of the rollers 17 are at all times 75 in the track 14, even when the carriage is at the limit of its travel and projects beyond the machine frame, as shown in Fig. 2. It will be seen from this figure also that the lugs 16 which support the carriage on the 80 rear guide rail 15 do not leave the guide rail at any time.

The carriage may be driven in letter-feed direction by a spring motor 18 mounted on the left-hand machine frame A, and connected through a band 19 to the carriage. 85 The letter-feed movement of the carriage in each printing zone is controlled by separate letter-feed mechanisms, each comprising a pinion 20 to run in mesh with a rack 21 on the carriage, said pinion connected to drive an escapement wheel 22 mounted coaxially with the pinion 20. The rotation of the escapement pinion 22 may be controlled as usual by escapement dogs 23 on a dog rocker 24 actuated by a universal bar 25, which is moved rearwardly by shoulders 26 on the type-bars 9. The escapement mechanism 90 may also be controlled and operated by a letter-space key 27, connected to a rock shaft 100 28 to which is also connected an arm 29 extending beneath a tail 30 on the dog rocker for swinging the latter each time the space key is depressed.

By reference to Fig. 4, it will be seen that 105 a separate escapement mechanism is provided for each set of keys, and also that the length of the carriage rack 21 is substantially equal to the distance between the centers of the pinions 20 and escapement 110 wheels. With this arrangement the carriage rack is brought within the control of the left-hand escapement mechanism simultaneously with its release from the control of the right-hand escapement mechanism. While 115 the carriage is in the right-hand printing zone the type keys 5, or space key 27 on the right-hand frame B may be operated to cause the letter-feed travel of the carriage to the left until the end of the writing line 120 has been reached, at which time the carriage assumes the position indicated in Figs. 1 and 3, and a further operation of said keys can have no effect on the carriage. As the rack bar has passed beyond the right-hand pinion 20, the carriage is prevented from running forward under the influence of the motor 18 by the left-hand end of the carriage rack being brought into mesh with the left-hand pinion 20. The carriage may now 125 130

either be returned for writing a new line in the right-hand zone or its movement to the left continued by operating the keys of the left-hand keyboard. It will thus be seen that the carriage passes directly from one zone into the other and is always in position to receive writing by the type keys of one set or the other. The position of the carriage is indicated by a pointer 31 on the carriage moving over a scale bar 32 mounted on the front rail 14, said scale bar comprising a right-hand scale 33 with numbered graduations and a similar left-hand scale 34. As the carriage passes directly from one printing point to the other, the highest scale marking on the right-hand scale coincides with the "0" point of the left-hand scale, as shown in Figs. 1 and 3.

It will be seen from Fig. 1 that when the carriage is at or near the limit of its letter-feed travel in the left-hand zone that the left-hand end of the carriage projects a considerable distance beyond the frame B and the roller 17 on the left-hand end of the carriage is supported on a portion of the front rail 14 over the right-hand frame A. Also the roller 17 on the right-hand end of the carriage runs on a portion of the rail over the frame B while the carriage is at or near the beginning of a line of writing in the left-hand zone. This arrangement, provided by using the same guide rail 14 for the carriage while in both the printing zones, permits the frames to be placed close together, whereas if two single frames having guide rails of the usual length were placed side by side with the ends of the guide rails abutting, a wide space would be required between the machine frames, with a corresponding increase in the total space required for the machine. In the present invention the total space required is reduced by eliminating the space between the frames. Also the central carriage roller 17 and one of the end rollers are always supported in the rail 14 providing stability of the carriage. The use of a single rear guide rail 15, as shown in Fig. 2, serves a like purpose in permitting the frames to be placed close together and allowing the bearing lugs 16 to be spaced a considerable distance apart to provide stability and at the same time retain said lugs on the guide rail during the entire travel of the carriage. The carriage rack 21 may be lifted from the escapement pinions 20 by the key 35 to permit the carriage to be moved freely in either direction from one point to another in either zone or from one printing zone to the other.

Variations may be resorted to within the scope of the invention, and portions of the improvements may be used without others.

Having thus described my invention, I claim:

1. In a typewriting machine, the combina-

tion with machine frames placed side by side and a set of type-bars and keys on each frame, of a paper carriage shiftable from the printing zone of one set to the printing zone of the other set, and having letter-feeding movements in each zone, the point at which the carriage leaves one zone being coincident with that in which it enters the zone of the other set.

2. In a typewriting machine, the combination with machine frames placed side by side, of separate type-systems on said frames, a paper carriage shiftable from position to coöperate with one type-system into position to coöperate with the other type-system, and a letter-feed mechanism associated with each type-system for controlling the letter-feed travel of the carriage in said system, the carriage being brought into the control of one letter-feed mechanism simultaneously with its movement beyond the control of the other letter-feed mechanism.

3. In a typewriting machine, the combination with separate sets of type-bars and keys for operating said type-bars, of a carriage movable from position to receive writing from one set of type-bars into position to receive writing from the other set of type-bars, escapement mechanism operated by one set of keys to control the letter-feed movement of the carriage, and a separate escapement mechanism operated by the other set of keys to control the letter-feed movement of the carriage, said carriage brought within the range of one escapement mechanism by the operation of the keys which actuate the other escapement mechanism.

4. In a typewriting machine, the combination with separate sets of type-bars and keys for operating said type-bars, of a carriage movable from position to receive writing from one set of type-bars into position to receive writing from the other set of type-bars, an escapement mechanism operated by one set of keys to control the letter-feed movement of the carriage, and a separate escapement mechanism operated by the other set of keys to control the letter-feed movement of the carriage, said carriage brought within the range of one escapement mechanism by the operation of the keys which actuate the other escapement mechanism, said carriage moved beyond the range of each escapement mechanism simultaneously with its movement into the range of the other escapement mechanism.

5. In a typewriting machine, the combination with separate key-systems, of a paper carriage, escapement mechanisms, one operated by each system of keys and each comprising an escapement pinion, and a rack on the carriage movable alternatively into engagement with said pinions.

6. In a typewriting machine, the combi-

nation with separate key systems, of a paper carriage, escapement mechanisms, one operated by each system of keys and each comprising an escapement pinion, and a rack on the carriage movable into engagement with

5 said pinions, the length of said rack being equal to the distance between the centers of said pinions.

7. In a typewriting machine, the combination with machine frames, of a type-system on each frame, a paper carriage shiftable from one system to the other, an escapement mechanism associated with each type-system and controlling the letter-feed travel 10 of the carriage in said system, the platen being brought within the influence of one escapement mechanism at an intermediate point at which it is freed from the control 15 of the other escapement mechanism, graduated scales to indicate the position of the carriage, the zero point on one scale coincident with the highest graduation on the other scale, and a pointer brought to said zero point when the carriage is at said intermediate point.

8. In a typewriting machine, the combination with separate escapement mechanisms, each comprising an escapement pinion, of a carriage, a rack thereon to run in mesh with either pinion, said rack having its leading end brought into engagement with one pinion as its other end leaves the other pinion, graduated scales indicating the position of the carriage, the zero point on 30 one scale corresponding with the highest graduation on the other scale, and a pointer on the carriage brought to said zero point when the carriage rack is in said position with its ends at said pinions.

9. In a typewriting machine, the combination with graduated scales, the zero point on one scale coincident with the highest graduation on the other scale, of a paper carriage, a pointer, said pointer and said 45 scales relatively movable during the travel of the carriage, and a plurality of type-systems having separate zones, one for each scale; said carriage movable into coöperation with either type-system.

10. In a typewriting machine, the combination with graduated scales, the zero point on one scale coincident with the highest graduation on the other scale, a paper carriage, a pointer thereon movable along said 55 scales during the travel of the carriage, and separate type-systems, one for writing while the pointer moves along one scale, and the other for writing while the pointer moves along the other scale.

11. In a typewriting machine, the combination with graduated scales, the zero point on one scale coincident with the highest graduation on the other scale, a paper carriage, a pointer thereon movable along said 65 scales during the travel of the carriage, sep-

arate type-systems, and an escapement mechanism for each type-system controlling the letter-feed travel of the carriage while said pointer is moving over one of said scales.

12. In a typewriting machine, the combination with machine frames placed side by side, of a type-system on each frame, a carriage shiftable from position to coöperate with one type-system into position to coöperate with the other, and having letter-feeding movements when coöoperating with each type-system, and a rail on which the carriage travels, said rail comprising a portion on which one portion of the carriage runs while coöperating with one type-system, and on which another portion of the carriage runs while coöperating with the other type-system.

13. In a typewriting machine, the combination with machine frames placed side by side, of a system of type-bars and keys mounted on each frame, said type-systems having separate printing centers, a paper carriage shiftable from one printing zone to the other, and having letter-feeding movements when coöperating with each type-system, and a rail on which said carriage runs, said rail comprising a portion forming a support for one end of the carriage when the latter is in one printing zone, said portion of the rail forming a support for the other end of the carriage during a portion of its travel in the other printing zone.

14. In a typewriting machine, the combination with machine frames placed side by side, of a set of type-bars and keys on each machine frame, escapement mechanisms operated by said sets, a paper carriage movable from one printing zone to the other, said carriage having a letter-feed movement in one printing zone controlled by one escapement mechanism, and in the other zone controlled by the other escapement mechanism, the carriage being brought into the control of one escapement mechanism as it leaves the control of the other escapement mechanism, graduated scales, and a pointer indicating on said scales the position of the carriage, the zero point on one scale corresponding with the highest graduation on the other scale, the pointer being at said zero point when the carriage is at the point of transfer from the control of one escapement mechanism to that of the other.

15. In a typewriting machine, the combination with separate letter-feed mechanisms, of a carriage having its letter-feed movements controlled by said mechanisms, said carriage moved by the operation of one mechanism within the range of the other.

16. In a typewriting machine, the combination with separate letter-feed mechanisms, of a carriage having its letter-feed movements controlled by said mechanisms,

said carriage moved by the operation of one mechanism within the range of the other simultaneously with its movement out of the range of the first mechanism.

5 17. The combination with machine frames placed side by side, of an open base on which said frames are mounted, said base comprising inwardly extending flanges, said machine frames having feet resting on said flanges, and bolts extending upward through said flanges and secured in the machine frames.

10 18. In a typewriting machine, the combination with a base, of machine frames mounted side by side thereon, brackets extending across the adjacent ends of the machine frames, and bolts securing said brackets to the frames.

15 19. In a typewriting machine, the combination with machine frames placed side by side and having their inner ends abutting, of front and rear brackets spanning said

ends, and means to secure said brackets to the frames.

20. In a typewriting machine, the combination with a base, of machine frames placed side by side thereon, brackets spanning the upper adjacent ends of the machine frames, and means for rigidly securing said base and brackets to the machine frames. 25

21. In a typewriting machine, the combination with a base, of machine frames placed side by side and comprising feet resting on the base, screw bolts extending upward through the base and threaded into 30 said feet, front and rear brackets on the upper surface of the inner ends of the machine frames, and screws rigidly connecting the brackets to the machine frames. 35
